COMBINED CONTAINER AND HAND PUMP FOR SPRAYING LIQUIDS OR THE LIKE

Frederick W. Muller, Shawnee Mission, Kans., and Juel D. Clevenger, Raytown, Mo., assignors to Cook Chemical Company, Kansas City, Mo., a corporation of Missouri

Filed Nov. 20, 1967, Ser. No. 9,479

Term of patent 14 years

U.S. Cl. D9—3
Int. Cl. D9—01

FIGURE 1 is a side elevational view of a combined container and hand pump for spraying liquids or the like, showing our new design;

FIG. 2 is a top plan view;

FIG. 3 is a fragmentary front elevational view; and

FIG. 4 is a fragmentary rear elevational view.

We claim:

The ornamental design for a combined container and hand pump for spraying liquids or the like, as shown.
